UNITED STATES PATENT OFFICE.

JOHN BYSTROM, OF CHICAGO, ILLINOIS.

HYDROCARBON-LAMP.

SPECIFICATION forming part of Letters Patent No. 703,384, dated July 1, 1902.

Application filed April 6, 1901. Serial No. 54,550. (No model.)

To all whom it may concern:

Be it known that I, JOHN BYSTROM, a citizen of the United States, residing at Chicago, in the county of Cook and State of Illinois, have invented certain new and useful Improvements in Hydrocarbon-Lamps, of which the following is a specification.

The object of this invention is to simplify and improve the construction and operation of hydrocarbon-lamps.

In the accompanying drawings, Figure 1 is a side elevation of a lamp-body having in its construction the features of my invention, the shell or casing for said lamp-body being represented in section. Fig. 2 is a vertical central section through the lamp-body. Fig. 3 is a top plan view of the same, the screens in the mixing-chamber having been removed. Fig. 4 is a transverse section on dotted line 4-4 of Fig. 1. Fig. 5 is an enlarged sectional view of the needle-valve. Fig. 6 is an enlarged front end view of the needle-stem, intended to show the flattened side of the stem and of the needle-point.

Like letters of reference indicate corresponding parts throughout the several views.

In the production of this lamp I provide a body portion A, comprising a central mixing-tube A', having at its upper end the enlarged mixing-chamber A². This mixing-chamber has the inner annular shoulder A³ about midway of its height, the upper end of said chamber being open. Within the bottom of said mixing-chamber is a semicircular row of holes A⁴ to provide subjects for assisting in heating the body portion of the lamp. On one side of the mixing-tube A', I provide an integral riser-tube A⁵, having the internally-screw-threaded socket A⁶ for the reception of the valve-pipe, to be later herein described. On the opposite side of the mixing-tube A' is the integral gas-tube A⁷, extending parallel with said mixing-tube and projecting to a point beyond the lower end of said tube. At its lower end the gas-tube A⁷ has a transverse extension A⁸, and said transverse extension has a longitudinal tube A⁹ alined with said mixing-tube A' and having a small opening A¹⁰ for the point of the needle-valve, to be later described herein. The tube A⁹ is provided with the internal screw-threads A¹¹ for receiving the externally-screw-threaded nee-

dle-valve stem, to be later described herein, and externally screw-threaded for receiving the initial heating-cup, which will also be described hereinafter.

A¹² is a stud formed integral with and projecting from the side of the mixing-tube A', which stud is internally screw-threaded. A rib A¹³, semicircular in outline, extends between the upper end of the riser-tube A⁵ and that of the tube A⁷. This rib is integral with the body-casting A, and its middle portion is formed with a hollow boss A¹⁴, internally screw-threaded to receive the screw-threaded plug A¹⁵ to close the outer end of the opening in said boss. The lower end of the riser-tube, the lower end of the gas-tube A⁷, and the outer end of the transverse extension A⁸ are closed by the screw-threaded plugs A¹⁶. The upper ends of the tubes A⁵ and A⁷ are connected by the ducts A¹⁷ and A¹⁸, formed by drilling from the interior of the hollow boss A¹⁴.

B is a tubular shell cut away in the elongated opening B' to receive the socket A⁶ and to permit said shell to be placed over the lamp-body, also provided with an opening B², adapted to coincide with the hollow screw-threaded stud A¹².

B³ is a screw adapted to pass through the opening B² in the shell B and enter the hollow stud A¹², its purpose being to secure the tubular shell in position upon the body portion of the lamp.

C is a supply-valve for regulating the flow of hydrocarbon to the lamp-body. The end of the pipe C' of the valve is externally screw-threaded to enter the socket A⁶.

D is the needle-valve stem externally screw-threaded to correspond with the interior of the tube A'. The upper end of this stem carries the needle-point D', (formed from a piece of wire secured in the end of the valve-stem,) which needle-point and the upper end of the stem are filed away on one side, and thus flattened to permit the escape of a small quantity of gas when the valve is nominally closed and to permit the burning of a small flame. The flattening of the needle-point also causes the needle to act like a reamer, scraping out the escape-opening A¹⁰ and keeping said opening free from soot and dirt.

D² is a generating-cup having the central

hub D³ internally screw-threaded to correspond with the screw-threads upon the needle-valve stem. The hub D³ is also provided with a larger central opening D⁴, extending 5 part way through the hub and internally screw-threaded to correspond with the external threads upon the vertical tube A⁹.

E is a screen, formed from wire-netting in disk form, adapted to fit within the mixing-chamber A² and rest upon the annular shoulder A³ therein. E' is also a wire screen, formed in cap shape, adapted to be inserted within the upper end of the mixing-chamber.

In operation gasoline is conducted to the body portion A by means of a pipe F, leading 15 to the supply-valve C. The hydrocarbon or the gas generated therefrom passes through the socket A⁶, through the riser-tube A⁵, into the ducts A¹⁷ and A¹⁸, passing intermediately 20 through the hollow boss A¹⁴, downward through the tube A⁷, outward through the transverse extension A, and upward through the needle-orifice A¹⁰ into the mixing-tube A'. In the mixing-tube it is combined with air 25 and is carried upward into the mixing-chamber A², where after passing through the screen E and the screen E' it enters the mantle (not shown) and is consumed upon the exterior surface of said mantle. A quantity of the 30 gas is projected downward through the openings A⁴ in the bottom of the mixing-chamber A², where it burns, constituting subjects, the purpose of which is to heat the body portion A. The wire screens E and E' are intended 35 to insure a thorough mixing of the gas.

The form of the needle-valve permits a minute but constant stream of gas to flow through the discharge-opening A¹⁰, and thus a small flame burns at all times at this point, even 40 when the needle-valve is closed tightly. The form of the needle D' and of the point of the valve-stem D prevents a clogging in the dis-

charge-opening A¹⁰, said needle acting as a reamer to keep the opening free from dirt and foreign substances.

While I have referred to the branches of the body portion as being tubular, they are so in fact only after holes are drilled in the cylindrical portions hereinbefore called "tubes," the outer ends of the holes formed by the 50 drill being closed by the plugs A¹⁶. The ducts A¹⁷ and A¹⁸ are drilled from the bottom of the hollow boss A¹⁴, both ducts being closed by the screw-plug A¹⁵.

I claim as my invention—

1. A needle-valve for hydrocarbon-lamps, having a valve-stem and a needle-point, said needle-point consisting of a wire fixed centrally of said valve-stem and at the forward end thereof, one-half of said point being cut 60 away along its axial diameter, and said valve-stem being flattened at its end to coincide with the flat side of the needle-point, in order to permit the escape of a small quantity of gas when the needle-valve is nominally closed. 65

2. The combination with a valve-casing having a tube with a stop-shoulder in said tube and a discharge-orifice, of a valve-stem adapted to lie within said tube and having a shoulder adapted to engage the stop-shoulder, 70 said valve-stem having a needle-point adapted to enter said orifice, which needle-point consists of a wire fixed centrally of said valve-stem at the forward end thereof, and being cut away at one side, said valve-stem also 75 being flattened at its end to permit the escape of a small quantity of gas when the shoulder of the valve-stem is in contact with the stop-shoulder of the tube.

JOHN BYSTROM.
